O. J. Martin. INVENTOR.

BY
Geo. P. Kimmel
ATTORNEY.

UNITED STATES PATENT OFFICE.

OSCAR J. MARTIN, OF GRAHAM, NORTH CAROLINA, ASSIGNEE, BY MESNE ASSIGNMENTS, TO H. D. LAMBETH, OF ELON COLLEGE, NORTH CAROLINA.

HAT AND COAT RACK.

Application filed November 18, 1921. Serial No. 516,133.

To all whom it may concern:

Be it known that I, OSCAR J. MARTIN, a citizen of the United States, residing at Graham, in the county of Alamance and State of North Carolina, have invented certain new and useful Improvements in Hat and Coat Racks, of which the following is a specification.

This invention relates to hat and coat racks and more particularly to the type known as costumers.

The object of the invention is to provide an article of this character which is both light and strong and presents an attractive appearance and is also capable of supporting umbrellas and catching the drip therefrom.

Another object is to provide improved means for bracing the rack and supporting the hangers.

With these and other objects in view, the invention consists in certain novel features of construction as hereinafter shown, described and claimed.

25 In the accompanying drawings:—

Figure 1 represents a side elevation of a rack constructed in accordance with this invention.

Fig. 2 is a top plan view thereof, and

30 Fig. 3 is a transverse section taken on the line 3—3 of Fig. 1.

In the embodiment illustrated, the device constituting this invention is composed of a plurality of laterally spaced uprights 1 in quadrature disposition here shown in the form of bars which may be composed of any suitable material, and which are connected at equi-distances apart by a plurality of longitudinally spaced superposed brace devices 3, 4 and 5, of different sizes and a chain 6, the latter is arranged between the brace devices 4 and 5. The brace devices and chain are preferably spaced equal distances apart, although not necessarily so.

45 The uprights or bars 1 as shown are curved inwardly throughout their length and flaring toward their lower ends. The bars which are equipped at their lower terminals with casters 2, in the form of semi-circular anti-scratching members such as are commonly used on articles of furniture.

The brace devices 3, 4 and 5, with the exception of being of different sizes with respect to each other, are alike in construction and arrangement, and only one of the said

brace devices will be described, as the description of one will apply to the other. The brace device 5 will be described in detail, and which consists of four bars 7, 8, 9 and 10, and each of which is secured at its outer end 60 to the inner face of one of the uprights 1. The bars 7 and 9, extend in parallel planes and the bars 8 and 10, extend in parallel planes, but the bars 8 and 10 are disposed at right-angles with respect to the bars 7 and 65 9. Each of the bars of the brace device, is of the same length, and the said bars are so disposed that the bars 8 and 10 extend in opposite directions with respect to each other, and a like arrangement is had with 70 respect to the bars 7 and 9. The inner ends of the bars 7 and 9, abut against the bars 8 and 10, and the inner ends of the bars 8 and 10, abut against the bars 7 and 9. The bars 7 and 9, abut against the bars 8 and 10, intermediate the ends of these latter and are secured thereto, and the bars 8 and 10, abut against the bars 7 and 9, intermediate the 75 ends of these latter, as well as being secured thereto, and by this arrangement, a rectangular open support is provided by the bars of each brace device. The upper of the brace devices 3, is of smaller size than the intermediate brace device 4, and the latter is of a smaller size than the lower brace device 5. 80 An umbrella drip cup 11 is mounted in the support formed by the bars of the lower brace 5, being removably held therein by means of a laterally extending flange 12 formed around the upper edge of the cup as 85 90 shown clearly in Fig. 3.

A central post 13 is mounted in the support formed by the bars of the brace devices 3 and 4, and secured therein by any suitable means. The said post 13 is of a length to 95 project at its upper end above the upper ends of the bars 1, as is shown clearly in Fig. 1, to improve the appearance of the rack and also to form a support for a hat or other article.

100 Mounted on the outer faces of the bars 1, at points registering with the bars of the brace devices 3 and 4, are a plurality of hangers or coat hooks 14. These hooks 14 are arranged directly opposite and in alignment with the bars 7, 8, 9 and 10 of the respective brace devices so that the strain exerted on these hooks by articles suspended therefrom will be borne not only by the bars 1, but by the arms or bars which form the 105 110

brace devices thereby preventing all danger of the bars 1 being forced outward and bent.

It is of course understood that the chain 6, is designed to support the handles of umbrellas the points of which are inserted in the drip cup 11, and hold them in proper position in the rack.

From the above description it will be obvious that a rack constructed as herein shown 10 and described may be decorated in any desired manner and composed of any desired material and that it will be light and readily portable from place to place and yet may be used to support a large number of hats, 15 coats, and other articles.

The preferred embodiment of the invention is disclosed in the drawings and set forth in the specification, but it will be understood that any modifications within the 20 scope of the claimed invention may be made in the construction without departing from the principle of the invention or sacrificing any of its advantages.

I claim:

25 1. A rack for the purpose set forth comprising a series of spaced standards, and a series of superposed spaced rigid brace devices arranged between the standards and each consisting of two pair of parallel bars, 30 the bars of each pair extending in opposite directions with respect to each other and with the bars of one pair having their inner ends secured to the bars of the other pair intermediate the ends of these latter, and with the outer ends of the bars of each pair 35 of bars secured to said standards corresponding in number to the number of bars of the brace device.

2. A rack for the purpose set forth comprising a series of spaced standards, and a series of superposed spaced rigid brace devices arranged between the standards and each consisting of two pair of parallel bars, 40 the bars of each pair extending in opposite directions with respect to each other and with the bars of one pair having their inner ends secured to the bars of the other pair intermediate the ends of these latter, and with the outer ends of the bars of each pair 45 of bars secured to said standards corresponding in number to the number of bars of the brace device, the inner ends of the bars of 50

one pair secured to the center of the bars of the other pair thereby providing a rectangular support.

55 3. A rack for the purpose set forth comprising a series of spaced standards, and a series of superposed spaced rigid brace devices arranged between the standards and each consisting of two pair of parallel bars, 60 the bars of each pair extending in opposite directions with respect to each other and with the bars of one pair having their inner ends secured to the bars of the other pair intermediate the ends of these latter, and with the outer ends of the bars of each pair 65 of bars secured to said standards corresponding in number to the number of bars of the brace device said brace devices of different size with respect to each other.

70 4. A rack for the purpose set forth comprising a series of spaced standards, a series of superposed spaced rigid brace devices arranged between the standards and each consisting of two pair of parallel bars, 75 the bars of each pair extending in opposite directions with respect to each other and with the bars of one pair having their inner ends secured to the bars of the other pair intermediate the ends of these latter, and with the outer ends of the bars of each pair 80 of bars secured to said standards corresponding in number to the number of bars of the brace device, the inner ends of the bars of one pair secured to the center of the bars of 85 the other pair thereby providing a rectangular support, and said brace devices of different size with respect to each other.

5. A rack for the purpose set forth comprising a series of standards, and a series 90 of superposed spaced rigid brace devices surrounded by the standards, each of said brace devices consisting of a series of bars, each of the bars of each brace device secured intermediate its ends to the inner end of one 95 of the other of the bars of the device thereby providing an open support, and each of the bars of each brace device projecting outwardly from the support and having its outer end secured to a standard.

100 In testimony whereof, I affix my signature hereto.

OSCAR J. MARTIN.
